TELEPHONE SYSTEM

Seth E. Peterson, Galva, Ill., assignor to Associated Electric Laboratories, Inc., Chicago, Ill., a corporation of Delaware

Application March 19, 1937, Serial No. 131,917

29 Claims. (Cl. 179—27)

The present invention relates to telephone systems and more particularly to such systems of the automatic step-by-step type having embodied therein apparatus automatically operable to permit the tracing of incoming calls to any desired predetermined subscriber's telephone.

Systems of the type mentioned conventionally comprise switch trains including step-by-step selector and connector switches for setting up and releasing connections between any pair of telephones in the system. In such systems, as well as in other systems of similar character, the need has long been recognized for means operable to assist an attendant in the tracing of incoming calls to particular telephones. This need arises in connection with repeated annoyance calls to certain telephones, in police work, and in rendering other services ordinarily required of a public exchange system. Various expedients have been resorted to in the past for providing this form of service. These expedients, however, leave something to be desired with respect to the simplicity of the apparatus involved and also with respect to the faithfulness of the operation thereof.

It is an object of the present invention, therefore, to provide an improved and exceedingly simple circuit arrangement, applicable to practically any of the various modifications of the step-by-step automatic telephone system, for assisting an attendant in tracing calls to any desired telephone embodied in the system.

More particularly, it is an object of the invention to provide an arrangement of the above character which utilizes to the fullest extent the switching equipment normally provided for rendering ordinary telephone service.

The invention as described in detail hereinafter is illustrated as being embodied in an automatic system employing a switch train of the step-by-step type, wherein line, selector and connector switches, operable in the order named, are provided for establishing a connection between a first or calling line to a second or called line. Such a connection may be regarded as comprising a talking loop between the two telephones, the loop being completed when the call is answered at the second or called telephone. In general, the objects as set forth above are realized in accordance with the present invention by providing means automatically operable as soon as the line associated with the telephone to be observed is seized by a connector switch, and maintained operated so long as the talking loop is not interrupted at the called telephone, for causing the

operation of an alarm device provided at the central exchange and for preventing the established connection from being released in response to any possible operation which the calling party may perform at the calling telephone, and more particularly in response to the interruption of the talking loop at the calling telephone. More specifically, this means comprises a plurality of interrelated relays associated with the line leading to the telephone to be observed, which relays operate when a connection is completed to this line to prevent the selector switch, preceding the operated connector switch, from being released when the calling party interrupts the talking loop at his telephone by hanging up his receiver. By holding this selector switch operated after the calling party hangs up, it is possible for the called party to inform an attendant at the central exchange that a call is to be traced, whereupon this attendant may, by observing the condition of the aforementioned selector switch and the line switch which has caused the operation thereof, determine the line on which the call was initiated. Additional means, comprising certain of the relays of the connector switch in use, are provided which are operable in case a talking loop is not completed at the observed telephone to cause the restoration of the above-mentioned means so that the connection may be released in the conventional manner when the calling party hangs up. As pointed out in detail hereinafter, the aforementioned relays are under the control of the answering party at the observed telephone and function to hold a predetermined potential, namely, ground potential, on the control conductor of the operated selector switch after the party at the calling telephone hangs up, whereby the portion of the switch train preceding the operated connector switch is held operated. The elements of the above-mentioned means are arranged in an exceptionally simple manner such that the control means normally provided in the various switches are utilized to the fullest extent in faithfully providing this form of service.

The novel features believed to be characteristic of the invention are set forth with particularity in the appended claims. The invention, both as to its organization and method of operation, together with further objects and advantages thereof, will best be understood by reference to the specification taken in connection with the accompanying drawing, in which the single figure thereof illustrates in partially schematic form a telephone system of the type mentioned, having embodied therein means constructed and

arranged in accordance with the present invention for assisting an attendant to trace calls to any desired telephone or telephones included in a system.

5 Referring now to the drawing, there is illustrated, for the purpose of describing the invention, an automatic telephone system of conventional form having embodied therein impulse responsive step-by-step switches for setting up and 10 releasing connections between any pair of telephone lines. In general, the system comprises a plurality of telephones or subscribers' substations, three of which are shown at A, B and C, adapted to be interconnected by means including their 15 respective associated subscribers' lines 10, 11 and 12 and switch trains including the aforementioned step-by-step switches. These switch trains, when established, may individually comprise the usual line switch associated with each 20 subscriber's line, a selector switch accessible to the line switch corresponding to the calling subscriber's line, and a connector switch accessible to the operated selector switch and having bank contacts in which the called subscriber's line 25 terminates. Thus, in the system shown, the lines 10, 11 and 12 terminate at line switches 13, 14 and 15, respectively, which switches have access to a group of selector switches, one of which is shown at 16. The latter switches, in turn, have 30 access to groups of connector switches, each connector switch of each group having its bank contacts multiplied to the bank contacts of the other switches in the same group and connected to serve a corresponding group of subscribers' 35 lines included in the system. Thus, the selector switch 16 has access to connector switches, one of which is shown at 17, in the bank contacts of which the subscriber's line 12 terminates. It is well known that by this arrangement, any subscriber 40 may, by proper manipulation of the impulsive device at his substation, establish a connection between his line and any other subscriber's line in the system.

45 Each of the line switches included in the system such, for example, as the line switches 13 to 15, inclusive, may be of any desired commercial construction, although preferably is of the well-known rotary type having three levels of bank contacts, wipers corresponding to the three levels, 50 a ratchet and pawl mechanism for driving the wipers, an operating magnet for actuating the ratchet and pawl mechanism, and control means whereby the operating magnet is energized when a call is initiated on the line associated with the 55 corresponding line switch and is de-energized when the wipers are rotated into engagement with a set of contacts corresponding to the first idle selector switch available. Similarly, each of the selector switches included in the system may be 60 of any desired form, although preferably is of the well-known Strowger type comprising bank contacts arranged in levels, each level corresponding to a particular group of connector switches, wipers for engaging the bank contacts, 65 ratchet and pawl mechanisms for imparting translatory and rotary movements to the wipers, vertical and rotary magnets for driving the respective ratchet and pawl mechanisms and control means whereby, when a selector switch is 70 first seized, it is automatically conditioned to be responsive to the first digit dialed at the calling substation, the dialing of the first digit causes the vertical magnet to step the wipers upward opposite the level of bank contacts corresponding 75 to the number of impulses in the digit dialed,

and the wipers are automatically rotated by the rotary magnet and associated ratchet and pawl mechanism into engagement with the set of contacts corresponding to the first idle connector in the group of connectors to which the called subscriber's line extends.

5 The various connector switches, like the selector switches, are preferably of the Strowger type and may be identical with that illustrated at 17. In brief, the switch 17 comprises two banks 10 of contacts arranged in levels, the individual contact sets connected to the various subscribers' lines being multiplied to the corresponding contact sets of other similar connector switches included in the same group. Thus, the switch 17 15 comprises a contact 45 in the control contact bank which contact is connected to the control or C conductor 19 leading to the line switch 15 associated with the subscriber's line 12. The corresponding line contacts 43 and 44 for the line 20 conductors 28 and 21 of the line 12 are included in the line contact bank. The connector switch 17 also includes wipers 40, 41, and 42 for engaging the various contact sets in the two contact banks, such for example, as the contacts 25 43, 44, and 45, a ratchet and pawl mechanism, not shown, for translating these wipers vertically opposite any desired contact level, a vertical magnet 125 for actuating this ratchet and pawl mechanism, a second ratchet and pawl mechanism, not 30 shown, for thereafter actuating the enumerated wipers into engagement with the particular contact set corresponding to the called subscriber's line, a rotary magnet 126 for driving this second ratchet and pawl mechanism, a release magnet 35 169 for tripping the ratchet and pawl mechanisms to permit the wipers 40-42, inclusive, to return to normal, and control means comprising a plurality of interrelated relays 100, 110, 120, 130, 140, 150, 160, and 170, their control and controlled 40 circuits and off-normal springs 147' and 148, for controlling the operation of the vertical and rotary magnets and for performing the various other functions normally required in this type of switch. More specifically, the last-mentioned 45 means comprise the relays 100 and 110, operative in the order named to condition the vertical magnet 125 for operation; the relay 120 and off-normal springs 147' for preventing the impulses 50 of the third digit, dialed at the calling substation, from being transmitted to the vertical magnet 125; the line relay 100 for interrupting the circuit of the vertical magnet 125 in accordance with the impulses of the second digit; the relays 110 and 120 for conditioning, at the end 55 of the second digit, the rotary magnet 126 to be responsive to the impulses comprising the third digit dialed at the calling substation; the relay 100 for interrupting the circuit of the rotary magnet 126 in accordance with the impulses of the third digit; the relay 140 for partially completing the connection to the called line, for applying ringing current thereto and for applying, in case the called line is found 60 idle, ring back current to the incompletely talking loop extending back to the calling subscriber's substation; the relay 150 for applying busy tone to this loop in case the called line is found busy and for preventing the calling line from being connected to the called line when this condition 65 prevails; the relay 160 for completing the connection between the calling and called lines, for interrupting the application of ringing current to the called subscriber's line and the application 70 of ring back current to the calling subscriber's 75

line; and the relay 170 for reversing battery back over the loop extending to the calling subscriber's line when the called party answers.

As pointed out in detail hereinafter, the relay 110, when operated to one of its two positions, includes closed contacts associated with its armature 111 for applying a predetermined potential, namely ground potential, to the control conductor 22 extending to the selector switch 16 thereby to hold the latter switch operated when a connection is once established by way of the switches 16 and 17 between two subscribers' lines. This relay is also operable to the other of its two positions, to remove, at the contacts noted, ground potential from the same control conductor, thereby to release, under certain conditions, the selector switch 16 when the talking loop is interrupted at the calling party's telephone.

Neglecting for the present the details of the connector switch 17 and the means associated therewith for assisting an attendant to trace calls to a predetermined subscribers' telephone or telephones, the system as described above is entirely conventional in form and its operation is well understood in the art. In brief, when a subscriber such, for example, as the subscriber at the telephone A initiates a call over the line 10 to a second subscriber's telephone such, for example, as the telephone C by lifting his receiver from its hook, the line switch 13 associated with the calling subscriber's line operates to select an idle selector switch and to condition the same to be responsive to impulses transmitted from the impulsing device at the telephone A. As noted above, each of the selector switches has access to one or more connector switches in which the subscribers' lines of the system terminate. Thus, if the selector switch 16, for example, is seized by the line switch 13, it operates in response to the dialing of the first digit at the substation A to translate its wipers vertically to a contact level corresponding to the group of connector switches at which the called line 12 terminates, following which it automatically rotates its wipers into engagement with a set of contacts corresponding to the first idle connector switch in this group such, for example, as the connector switch 17. Thereafter, and in response to the dialing of the second digit, the connector switch, through the operation of its vertical magnet and the associated pawl and ratchet mechanism, translates its wipers vertically to positions opposite the respective levels of bank contacts in which the conductors 19 to 21, inclusive, of the called subscriber's line, terminate. With the switch train in this condition and when the final or third digit is dialed, the rotary magnet of the connector switch, in cooperation with its associated ratchet and pawl mechanism, operates to drive the wipers 40 to 42, inclusive, into engagement with the contacts 43 to 45, inclusive, corresponding to the called line 12.

The system conventionally includes means whereby ringing current and ring back tone are automatically transmitted respectively, to the substations of the called and calling parties in case the called line is idle and upon the connector wiper coming into engagement with the bank contacts at which the called subscriber's line terminates. Also, in accordance with conventional practice, means are provided whereby, in the event the called line is found busy, the calling line is not connected thereto and busy tone is transmitted back over the established loop to

the calling party to indicate the busy condition of the called line.

In the event the called line is found idle and the called party answers, battery is reversed back over the loop when the called party lifts his receiver from its hook to connect a bridge across the conductors of the called line. With the system in this condition, a talking connection is established between the calling and called parties which obtains until the conversation is terminated and one of the parties hangs up.

The arrangement is such that, when the calling party is the first to interrupt the talking loop by hanging up, the switch train leading to the connector switch 17 and including the selector switch 16 and the line switch 13 is normally released. The connector switch is, however, held in its operated position until the called party hangs up to remove the bridge from across the conductors of his line. In the event the called party is the first to interrupt the talking loop, the entire switch train is maintained operated until the calling party hangs up.

More particularly, the operation of the connector switch 17, in the above described sequence of operations, is initiated when the selector switch 16 seizes this connector in response to the dialing of the first digit at the calling substation by causing a bridge to be connected across the line conductors 30 and 31, thereby to complete a circuit for energizing the relay 100. This circuit extends from ground at the lower winding of the relay noted, through this winding, by way of the armature 174 and its associated contact 174' of the relay 170, the conductor 29, the line conductor 31, through the bridge across the conductors 30 and 31, over the conductors 30 and 28, and through the armature 173 and its associated contact 173' and the upper winding of the relay 100 to battery. When energized over the above-traced circuit, the relay 100 operates to complete, at its armature 101 and associated contact 103, a circuit for energizing the slow-to-release hold relay 110. The last-mentioned relay in turn operates to connect, at its armature 111, ground to the control or C conductor 22, to prepare, at its armature 112, holding circuits for the relays 140 and 160 and to prepare, at its armature 113 and associated contact 114, a circuit for energizing the series connected vertical magnet 125 and relay 120. With the hold relay 110 in its operated position, the ground applied to the control conductor 22 at the armature 111 holds the switch train including the selector switch 16 and preceding the connector switch 17 in its operated condition. With the control means of the connector switch 17 in this condition, the vertical magnet 125 is conditioned to be responsive to impulses transmitted from the impulsing device at the calling subscriber's telephone A.

At the beginning of the first impulse of the second digit, the bridge across the line conductors 30 and 31 is interrupted, thereby to open the previously traced operating circuit for the line relay 100, permitting this relay to restore and complete, at its armature 101, the previously prepared circuit for energizing the relay 120 and the vertical magnet 125 in series. The last-mentioned circuit extends from ground at the armature 101 and its associated contact 102, through the operated armature 113 and associated contact 114, the contacts 126 and 127 of the off-normal springs 147', the winding of the relay 120, and through the winding of the ver-

tical magnet 125 to battery. When the slow-to-release relay 120 operates, it prepares, at its armature 121 and associated contact 122, an obvious multiple energizing circuit for itself and the vertical magnet 125. At the beginning of the first impulse when the line relay 100 falls back to complete the operating circuit of the vertical magnet 125, the ratchet and pawl mechanism associated with the vertical magnet causes the wipers 40, 41 and 42 to be translated one step vertically. This first step of the switch also causes the off-normal contacts 147' and 148 to be operated so that the contacts 126 and 127 are opened, the contacts 124 and 128 are closed and the contacts 129 and 149 are closed. Closure of the last-mentioned contacts prepares an obvious circuit for energizing the release magnet 169, and closure of the off-normal contacts 124 and 128 completes the previously prepared multiple circuit for energizing the relay 120 and the vertical magnet 125. The completion of the last-mentioned multiple circuit permits the vertical magnet alternately to be energized and de-energized in accordance with the operation and restoration of the line relay 100 corresponding to succeeding impulses of the digit being dialed. Thus, the wipers 40 to 42, inclusive, are stepped vertically into a position opposite the level in which the called line terminates and corresponding to the impulses of the dialed digit.

At the end of the second digit, the circuit for energizing the line relay 100 is closed so that the previously traced circuit for the relay 120 and the vertical magnet 125 is interrupted at the armature 101. Accordingly, the relay 120 restores after an interval, opening, at its armature 121 and associated contact 122, the previously mentioned multiple circuit for itself and preparing, at the same armature and its associated contact 123, a circuit extending by way of the conductor 37, the armature 154 and the armature 145 for energizing the rotary magnet 126 and the slow-to-release relay 130 in parallel. At the beginning of the first impulse of the second digit, the line relay 100 again restores, to complete, at its armature 101, the prepared circuit for energizing the rotary magnet 126 and the relay 130. In response to such energization, the relay 130 operates to interrupt, at its armature 131 and associated contact 132, a point in the circuit for energizing the lower winding of the relay 140 and to connect at this same armature the directing or control wiper 42 to the upper terminal of the winding of the relay 150 over a path extending by way of the armatures 131 and 133, the armature 142 and the conductor 35. At its armature 135, the relay 130 closes a shunt around the armature 154 of the relay 150. During succeeding impulses of the second digit, the circuit for the relay 130 and the rotary magnet 126 is alternately interrupted and completed at the armature 101 of the line relay 100, in accordance with the impulses of this digit, whereby the rotary magnet causes its associated ratchet and pawl mechanism to step the wipers 40 to 42, inclusive, into engagement with the bank contacts 43 to 45, inclusive, to which the line conductors of the called line 12 are connected. During these impulses, the relay 130, due to its slow-to-release characteristic, remains operated and, at its armature 135, maintains a shunt around the armature 154 of the relay 150 so that the circuit to the rotary magnet is not opened at the last-mentioned armature when the control wiper 42 passes over contacts corresponding to busy lines to cause energization of the relay 150.

In the course of this stepping operation and each time the directing wiper 42 engages a contact corresponding to a busy line, the relay 150 operates, but without effect at this time. At the conclusion of the series of impulses comprising the third digit, the relay 100 remains in its operated position so that the circuit for energizing the relay 130 and the rotary magnet 126 is interrupted. As a consequence, and providing the called line 12 is idle, the relay 130 falls back after an interval 10 to again prepare, at its armature 131 and associated contact 132, a circuit for energizing the lower winding of the relay 140.

If the called line is idle, and when the relay 130 restores, a circuit is completed for partially 15 energizing the relay 140, this circuit extending from battery at the cut-off relay in the line switch associated with the called line 12, over the control conductor 19, through the contact 45, the wiper 42, the armature 131 and associated 20 contact 132, over the conductor 38, through the lower winding of the relay 140, over the conductor 39, through the contact 152 and associated armature 151 of the relay 150, and over the release trunk or control conductor 22 to ground at the 25 armature 111. The relay 140 partially operates in response to such partial energization, to complete, at its armature 144, its previously prepared locking circuit extending by way of the conductor 25 to ground at the armature 112, thereby 30 to cause the full operation thereof. When this occurs, the connection to the called line is partially completed at the armatures 141 and 146, direct ground is connected to the control conductor 19 at the armature 147, ground is connected to the ringing interrupter start conductor 23 at the armature 143, the circuit for energizing the relay 150 is interrupted at the armature 142, and the circuit for energizing the rotary magnet 126 is interrupted at the armature 145. 40

When the ringing interrupter is started, ringing current is transmitted to the bell at the called substation over a circuit extending from the ringing generator by way of the conductor 46, the armatures 168 and 146, the wiper 40 and associated contact 43, the line conductor 21, the bridged bell and condenser at the called party's substation, the conductor 20, the contact 44 and associated wiper 41, the armatures 141 and 161, the conductor 34, and through the lower winding of the relay 160 and battery to ground. Due to the alternating nature of this ringing current, a voltage of the same frequency is induced in the upper winding of the relay 160. This voltage is impressed across the terminals of the receiver at the calling substation over a path which includes the conductor 66, the lower winding of the relay 170 and the line conductor 31. Due to the slow-to-operate characteristic of the relay 160, this relay does not operate during the ringing operation. In this manner, the called substation is signaled and the calling party is notified that the called line is idle. 50

When the called party at the telephone C answers the call by lifting his telephone receiver 65 from its hook, a direct current circuit is completed for energizing the lower winding of the relay 160, this circuit extending from ground on the conductor 46, through the armatures 168 and 146, the wiper 40, the contact 43, over the conductor 21, through the bridge at the called substation, over the line conductor 20, through the contact 44, the wiper 41, the two armatures 141 and 161, and the lower winding of the relay 160 to battery. The relay 160 now operates to close 70 75

an obvious locking circuit for itself at its armature 167, to complete the talking loop between the calling and called substations at its armatures 161 and 168, to interrupt its original energizing circuit at its armature 161 and associated contact 162, to interrupt, at its armature 165 and associated contact 164, the circuit for the ringing interrupter, to interrupt at its armature 168 and the lower associated contact the previously traced 10 ringing current circuit, thereby to discontinue the application of ringing and ring-back tones to the loops extending to the called and calling parties, respectively, and to complete, at its armature 165 and associated contact 166, a circuit for lighting 15 the supervisory lamp No. 1. When the locking circuit for the relay 160 is completed, a circuit is also completed for energizing the battery reversing relay 170, this circuit extending from ground at the armature 112 by way of the conductor 25, 20 the armature 161, the conductor 66, the lower winding of the relay 170, the armatures 168 and 146, over the line conductor 21, through the bridge at the called substation, back over the line conductor 20, through the armatures 141 and 161, 25 over the conductor 26, and through the upper winding of the relay 170 to battery. When the relay 170 operates, it interrupts, at its armature 171, the previously completed circuit for energizing the supervisory lamp No. 1, interrupts, at its 30 armature 176, the previously prepared circuit for the release magnet 169, prepares at this same armature a circuit for energizing the supervisory lamp No. 2 and, at its armatures 172 and 175 and their respective associated contacts 173 and 174, 35 reverses battery back over the loop extending to the calling substation for the purpose of operating a coin collector or meter, if such service is desired. Operation of the armature 171 also completes a multiple locking circuit for the relays 40, 140, 160 and 170, this circuit extending from ground at the armature 143 by way of the conductor 36, the armature 165, the conductor 24 and through the armature 171 to the conductor 25 where the circuit divides into three branches, 45 one for each of the windings of the three enumerated relays.

Before describing the release of the connection as established in the above manner, it will be assumed that, instead of being idle, the called substation C is found busy at the time the wipers 40 to 42, inclusive, are stepped into engagement with the contacts 43 to 45, inclusive, corresponding to the conductors of the called line. When this occurs, ground is present on the release conductor 19 so that the wiper 42, upon engaging the contact 45, completes an obvious circuit for energizing the relay 150. This relay operates to prepare, at its armature 151, a locking circuit for itself, which circuit is completed when the relay 50 130 restores after an interval, following the end of the third impulse digit. This circuit extends from ground at the armature 111 by way of the control conductor 22, the armature 151 and associated contact 153, the contact 134 and its associated armature 133, the armature 142, the conductor 35, and through the winding of the relay 150 to battery. In its operated position, the relay 150 opens, at its armature 154, the original circuit for energizing the relay 130 and the rotary magnet 126 and, at its armature 155, applies busy tone to the lower line conductor 31 to notify the calling subscriber A that the called line C is busy.

Continuing now with the operation of the connector switch during the release of an established

connection, when the conversation is concluded and the calling party A replaces his telephone on its hook, the bridge across the line conductors 30 and 31 holding the line relay 100 operated, is removed. As a result, the relay 100 restores, 5 opening, at its armature 101 and associated contact 103, the operating circuit for the relay 110, which latter relay, after an interval, also restores. When the relay 110 falls back it interrupts, at its armature 112, the original holding circuit for 10 the relays 160 and 140, prepares, at its armature 113 and associated contact 115, a circuit for energizing the release magnet 169 and, at its armature 111, removes ground from the control conductor 22. The relay 100, upon restoring and 15 before the relay 110 falls back, completes, at its armature 101 and associated contact 102, the previously traced circuit for energizing the relay 130. When the relay 130 operates, it removes, at its armature 131, the multiple ground from the 20 control conductor 22, which ground extends by way of the armature 147, the armature 131 and associated contact 132, the conductor 38, the lower winding of the relay 140, the conductor 39, and the armature 151. By removing this multiple 25 ground from the conductor 22, the release of the switch train preceding the connector 17 is placed under the control of the relay 110. Thus, when the relay 110 restores, following the operation of the slow-to-release relay 130, it, for an interval, 30 completely removes, at its armature 111, ground from the conductor 22, thereby permitting the selector switch 16 and the line switch 13 to be released, in the order named, in a manner well understood in the art. 35

When the relay 110 restores, shortly after the restoration of the relay 100, it not only effects the release of the switch train preceding the connector 17, but interrupts, at its armature 113, the circuit for energizing the relay 130, permitting this relay to restore, which it does after an interval, thereby to return ground to the control conductor 22 from the armature 147 of the connector switch and thus mark the switch 17 as busy in the selector switch contact banks until 45 the connection is cleared out at the called substation. Restoration of the relay 110 also completes an obvious circuit for energizing the supervisory lamp No. 2, which circuit extends from ground at the armature 101 and its associated contact 102, 50 through the armature 113 and associated contact 115, the armature 176, and the supervisory lamp to battery. Although the original locking circuit for the relays 160 and 140 is opened, at the armature 112, these relays are retained operated over the previously traced multiple locking circuit extending from ground at the armature 143. It is to be observed at this point that the connector switch 17 is still held in its operated position by virtue of the fact that the circuit to 55 the release magnet 169 is held open at the armature 176 of the battery reversing relay 170.

When the party at the called substation C hangs up, the circuit to the relay 170 is interrupted by the removal of the bridge at the called 65 substation from across the line conductors 20 and 21, permitting this relay to restore and complete, at its armature 176, a circuit for the release magnet 169, this circuit extending from ground at the armature 101 by way of the armatures 113 and 176, the closed off-normal contacts 148, and through the winding of the magnet 169 to battery. The release magnet thereupon, in a well-known manner, actuates its associated ratchet mechanism to permit the wipers 70 75

- 40 to 42, inclusive, to be restored to normal. When the wipers reach their normal or home positions, the off-normal springs 148 and 147 are restored to normal in a well-known manner. 5 Restoration of the relay 170 also causes the multiple locking circuit for the relays 140 and 160 to be opened at the armature 171, whereby these relays are permitted to restore. Thus, the control equipment included in the connector switch 10 17 is restored to normal and the switch is ready for further use.

In the event the talking loop is interrupted at the called substation C before the calling party at the substation A hangs up, the relay 170 15 is the first to fall back. This relay thereupon interrupts, at its armature 171, the multiple locking circuit for the relays 140 and 160 and prepares, at its armature 176, a circuit for energizing the release magnet 169. Under the conditions stated, the entire switch train including the connector 17 is held in its operated condition until the talking loop is interrupted at the calling substation A. When this occurs, the relay 100 restores to cause the reoperation of the 20 relay 130 and to interrupt the circuit for the holding relay 110. The relay 130, upon reoperating, removes multiple ground from the control conductor 22 so that, when the relay 110 restores its armature 111, the switch train comprising 25 the selector switch 16 and the line switch 13 is released and automatically restores to normal. The steps which follow the restoration of the relays 100 and 110 are, from this point on, exactly 30 the same as those described in the preceding paragraphs.

As pointed out above, occasions arise when it is extremely desirable to be able to trace calls to one or more telephones included in the system. In accordance with the present invention, 35 means are provided, operable when a connection is once established to a called line and maintained operated so long as the established talking loop is not interrupted at the called telephone, for preventing the means comprising the relay 110 from initiating the release of the connection in the manner described above. More 40 specifically, this means comprises the relays 180 and 190 which, when operated, retain ground potential upon the control conductor 22 independently of the relay 110 and thereby prevent 45 the release of the switch train comprising the line switch associated with a calling line and the selector switch seized by such a line switch. The relay 180 has its winding connected between battery and the release trunk conductor such, for 50 example, as the conductor 19, of the subscriber's line it is desired to observe. It will be understood that this conductor for each of the subscriber's lines of the system is multiplied to the bank contacts of the group of connector switches at which 55 the line terminates, so that, in the event any of these connector switches is seized on an incoming call to the line 12, the relay 180 is operated. When this relay operates, it completes, at its 60 armature 181, a circuit for energizing the relay 190. The last-mentioned relay has a number of armatures, one for each of the connector switches in which the conductors of the line 12 are multiplied. Each of these armatures extends to the 65 conductor corresponding to the conductor 24 of the switch 17, and their respective associated contacts are individually connected to the respective control conductors of the corresponding connector switches. Thus, the armature 191 is connected by means of a conductor 60 to the con-

ductor 24 and the contact associated with the armature 191 is connected over a conductor 61 to the control conductor 22. An additional armature 195 and associated contact is embodied in the relay 190 for closing a circuit for energizing 5 an alarm such, for example, as a bell. Such an alarm is schematically indicated at 62.

With the above arrangement it is to be observed that the relay 110 when in one of its two positions, namely, its operated position, applies a predetermined potential, i. e., ground potential, to the control conductor 22 to hold the selector switch 16 and the preceding switch or switches operated. In the other of its two positions, or its restored position, this relay removes ground potential from the control conductor 22 to release the switch train. It will further be apparent that the conductors 60 and 61 comprise a normally uncompleted path for applying this same predetermined potential to the control conductor independently of the relay 110, this path extending from ground at the armature 143, by way of the conductor 36, the armature 165 and associated contact 166, the conductor 60, the armature 191, and the conductor 61, and being fully completed 25 when the relay 160 operates following the completion of the talking loop between the calling and called telephones.

In the operation of the above-described arrangement and assuming that it is desired to 30 observe incoming calls to the subscriber's line 12, immediately upon the establishing of a connection to this line and when the wiper 42 engages the bank contact 45, a circuit is completed for energizing the relay 180, this circuit extending 35 from ground at the armature 147 by way of the wiper 42, the bank contact 45, the conductor 64 and through the winding of the relay 180 to battery. The last-mentioned relay operates and, at its armature 181, completes a circuit for energizing the relay 190, which relay, in turn, closes 40 all of its armatures 191, 192, 193, 194, etc., to their respective associated contacts. The closure of the armature 195 to its associated contact initiates the operation of the alarm device 62, 45 thereby indicating to an attendant in the exchange wherein the connector switch 17 is located that a call is being made to the line to be observed. If the called line is answered, the attendant may, by connecting a telephone across 50 the conductors 30 and 31 at the test jack 65, converse with the called party and determine whether or not the call is to be traced. It will be observed that, when the attendant plugs his 55 telephone into the contacts of the jack 65, ground is applied to the control conductor 22 from the spring 66, so that the switch train preceding the connector switch 17 is held operated independently of the condition of the telephones at either of the substations A or C. If the call is to be 60 traced, the attendant may, by observing the condition of the selector switch 16 and the line switch 13, determine the line from which the call was initiated.

It is the function of the means comprising the 65 relays 180 and 190 to prevent the switch train from being released in case the calling party 70 interrupts the talking loop immediately after its completion and before the attendant can receive instructions as to whether or not the call should 75 be traced. Thus, let it be assumed that the calling party hangs up shortly after the call is answered at the called substation. When this occurs, multiple ground is removed from the control conductor 22 at the armature 131 of the 75

relay 130, and the relay 110 restores as described above. When the relay 110 restores, it removes ground from the control conductor 22 at its armature 111 and normally this last operation would permit the switch train comprising the selector switch 16 and the line switch 13 to be released. Due to the completion of the previously traced path including the conductors 60 and 61, however, ground is maintained on the control conductor 22. The switch train preceding the connector switch 17 is, therefore, held in its operated condition until such time as the call is cleared out at the called substation. Also, and as described previously, the relays 170, 140 and 160 are held operated by virtue of the multiple locking circuit extending from ground at the armature 143, until such time as the loop is interrupted at the called telephone. With the system in this condition and when the loop is interrupted at the called substation by the called party replacing his receiver on its hook, the relays 170, 160 and 140 restore, in the order named. The first-mentioned of these relays upon falling back completes, at its armature 178, the circuit for the release magnet 169 causing this magnet to operate. As a consequence the wipers 40-42, inclusive, are restored to normal and the circuit holding the relay 180 operated is interrupted permitting this relay to restore and open the circuit holding the relay 190 operated. Thereupon, the relay 190 restores to interrupt, at its armature 191, the previously traced path including the conductors 60 and 61 holding ground on the control conductor 22, thereby permitting the switch train preceding the connector switch 17 to be released.

It will be evident that in an instance when the line to the telephone under observation is seized by a connector switch, but the call is not answered, the switch train should be subject to release when the connection is interrupted at the telephone of the calling party. To insure this mode of operation there is provided means operable in case the talking loop between the calling and called parties is not completed for causing the release of the switch train utilized in setting up the connection. This means comprises the relays 100 and 110 and the release magnet 169.

Thus, when this condition prevails, the battery reversing relay 170 is not operated and, consequently, when the relays 100 and 110 restore, in the order named, in response to the interruption of the connection at the calling telephone, the circuit for energizing the release magnet is completed. The wipers 40-42, inclusive, thereupon, are restored to their respective normal positions and the operating circuit for the relay 180 is opened. This relay upon falling back in turn opens the operating circuit of the relay 190. When the last-mentioned relay restores it interrupts the path including the conductors 60 and 61 for applying ground potential to the control conductor 22 independently of the contacts associated with the armature 111. Hence the switch train preceding the connector switch 17 is permitted to restore to its normal condition and the connection is cleared out.

As pointed out previously, the arrangement of the system is such that when the line to be observed is seized by any one of the group of connector switches in the bank contacts of which this line is multipled, ground is present on the conductor 64 and the relays 180 and 190 are operated. Hence, all of the armatures 191, 192, 193, etc., are closed to their respective associated

contacts and the paths for applying ground potential to the respective control conductors of the connector switches included in the group, independently of their respective hold relays such, for example, as the relay 110, are prepared. Since, however, the relays 140, 160 and 170 do not operate when the connector switch 17 attempts to seize the line 12, the alternative path for applying ground potential to the control conductor 22 is not completed. As a result the switch train leading to the busy line is releasable under the control of the calling party.

From the foregoing description it will be apparent that under any conditions following the completion of a talking loop between a calling substation and the substation under observation, it is possible to trace a call to a line which it is desired to observe.

While there has been described what is at present considered to be the preferred embodiment of the invention, it will be understood that various modifications may be made therein, and it is contemplated to cover in the appended claims all such modifications as fall within the true spirit and scope of the invention.

I claim:

1. In a telephone system, a first telephone, a second telephone, means for establishing a connection between said telephones on a call from said first telephone to said second telephone, said connection comprising a talking loop adapted to be completed when the call is answered at said second telephone, said means normally being released when said talking loop is interrupted at said first telephone, an alarm device, means responsive to the operation of said first-named means for causing the operation of said alarm device, and means responsive to the completion of said talking loop for preventing the release of said first-named means, whereby calls to said second telephone may be traced by an attendant.

2. In a telephone system, a first telephone, a second telephone, means for establishing a connection between said telephones on a call from said first telephone to said second telephone, said connection comprising a talking loop adapted to be completed when said call is answered at said second telephone, said means normally being released when the talking loop is interrupted at said first telephone, an alarm device, and means automatically operable during the establishing of the connection and maintained operated so long as said talking loop is not interrupted at said second telephone for causing the operation of said alarm device and for preventing the release of said first-named means, whereby calls to said second telephone may be traced by an attendant.

3. In a telephone system, a first telephone, a second telephone, means for establishing a connection between said telephones on a call from said first telephone to said second telephone, said connection comprising a talking loop adapted to be completed when said call is answered at said second telephone, said means normally being released when said talking connection is interrupted at said first telephone, an alarm device, means automatically operable during the establishing of said connection and maintained operated so long as said talking loop is not interrupted at said second telephone for causing the operation of said alarm device and for preventing the release of said first-named means, whereby calls to said second telephone may be traced by an attendant, and means operable in

case said talking loop is not completed for rendering said second-named means ineffective, so that said connection may be released.

4. In a telephone system, a first telephone, a second telephone, means including a switch train for establishing a connection between said telephones on a call from said first to said second telephone, said connection comprising a talking loop adapted to be completed when said call is answered at said second telephone, said switch train including means for initiating the release of said connection when said talking loop is interrupted at said first telephone, an alarm device, and means operable during the establishing of said connection and maintained operated so long as said talking loop is not interrupted at said second telephone for causing the operation of said alarm device and for preventing the operation of said second-named means from releasing said connection, whereby calls to said second telephone may be traced by an attendant.

5. In a telephone system, a first telephone, a second telephone, means including a switch train for establishing a connection between said telephones on a call from said first telephone to said second telephone, said connection comprising a talking loop adapted to be completed when said call is answered at said second telephone, said switch train including means for initiating the release of said connection when said talking loop is interrupted at said first telephone, an alarm device, means operable during the establishing of said connection and maintained operated so long as said talking loop is not interrupted at said second telephone for causing the operation of said alarm device and for preventing the operation of said second-named means from releasing said connection, whereby calls to said second telephone may be traced by an attendant, and means operable in case said talking loop is not completed for rendering said third-named means ineffective, so that said connection may be released.

6. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including means for completing the connection to the line associated with said second telephone and means normally operable to initiate the release of the connection in response to the interruption of said talking loop at said first telephone, an alarm device, and means responsive to the operation of said second-named means for causing the operation of said alarm device and for preventing said third-named means from initiating the release of said connection, whereby calls to said second telephone may be traced by an attendant.

7. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including means for completing the connection to the line associated with said second telephone and means normally operable to initiate the release of the connection

in response to the interruption of said talking loop at said first telephone, an alarm device, and means operable in response to the operation of said second-named means and maintained operated so long as said talking loop is not interrupted at said second telephone for causing the operation of said alarm device and for preventing said third-named means from initiating the release of said connection, whereby calls to said second telephone may be traced by an attendant. 10

8. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including means for completing the connection to the line associated with said second telephone and means normally operable to initiate the release of the connection in response to the interruption of said talking loop at said first telephone, an alarm device, means operable during the establishing of said connection and maintained operated so long as said talking loop is not interrupted at said second telephone for causing the operation of said alarm device and for preparing a circuit for preventing said third-named means from initiating the release of said connection, means responsive to the operation of said second-named means for completing said circuit, whereby calls to said second telephone may be traced by an attendant, and means operable in case the talking loop is not completed for preventing the completion of said circuit so that said connection may be released. 30

9. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including a selector switch and a connector switch for completing the connection to the line associated with said second telephone, means included in said connector switch and normally responsive to the interruption of said talking loop at said first telephone for releasing said selector switch, an alarm device, and means automatically operable during the establishing of said connection for causing the operation of said alarm device and for preventing said last-named means from releasing said selector switch, whereby calls to said second telephone may be traced by an attendant. 40

10. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including a selector switch and a connector switch for completing the connection to the line associated with said second telephone, means included in said connector switch and normally responsive to the interruption of said talking loop at said first telephone for releasing said connection, an alarm device, means operable during the establishing of said connection for causing the operation of 60

said alarm device and for preventing said last-named means from releasing said selector switch, whereby calls to said second telephone may be traced by an attendant, and means operable in 5 case said talking loop is not completed for rendering said last-named means ineffective, so that said connection may be released.

11. In a telephone system, a first telephone, a second telephone, a line switch associated with 10 said first telephone, a selector switch, a connector switch, means including said switches, operative in the order named, for establishing a connection between said telephones on a call from said first telephone to said second telephone, said connection comprising a talking loop adapted to be completed when said call is answered at said second telephone, means included in said connector switch and normally operative to release said line switch and said selector 15 switch when said talking loop is interrupted at said first telephone, an alarm device, and means operated during the establishing of said connection and maintained operated so long as said talking loop is completed for causing the operation 20 of said alarm device and for preventing the release of said line and selector switches, whereby calls to said second telephone may be traced by an attendant.

12. In a telephone system, a first telephone, 30 a second telephone, lines individually associated with said telephones, means including a selector switch and a connector switch, operable in the order named, for establishing a connection between said lines on a call from said first telephone to said second telephone, said connection comprising a talking loop adapted to be completed when the call is answered at said second telephone, said selector switch including a control conductor, means comprising a relay in said 35 connector switch for applying a predetermined potential to said control conductor to hold said selector switch operated, said relay being operable from one of its two positions to the other to remove said potential from said control conductor and thereby release said selector switch 40 when said talking loop is interrupted at said first telephone, an alarm device, and means operable during the establishing of said connection and maintained operated so long as said talking 45 loop is not interrupted at said second telephone for causing the operation of said alarm device and for maintaining said predetermined potential on said control conductor independently of said relay.

13. In a telephone system, a first telephone, a second telephone, lines individually associated with said telephones, means including a selector switch and a connector switch, operable in the order named, for establishing a connection between said lines on a call from said first telephone to said second telephone, said connection comprising a talking loop adapted to be completed when the call is answered at said second telephone, said selector switch including 55 a control conductor, a line relay in said connector switch operated to one of its two positions in response to the seizure of said connector switch by said selector switch, a second relay operated to one of its two positions in response to the operation of said line relay to its 60 said one position, means responsive to the operation of said second relay to its said one position for conditioning said connector switch to complete said connection, said second relay including contacts, closed when said second relay 65 is in said one of said positions.

lay is operated to said one position, for applying a predetermined potential to said control conductor thereby to hold said selector switch operated, said second relay being operable from its said one to the other of its two positions to remove said potential from said control conductor and thereby release said selector switch when said talking loop is interrupted at said first telephone, an alarm device, and means operable during the establishing of said connection 10 and maintained operated so long as the talking loop is not interrupted at said second telephone for causing the operation of said alarm device and for maintaining said predetermined potential on said control conductor independently of 15 said relays.

14. In a telephone system, a first telephone, a second telephone, lines individually associated with said telephones, means including a selector switch and a connector switch, operable in the 20 order named, for establishing a connection between said lines on a call from said first telephone to said second telephone, said connection comprising a talking loop adapted to be completed when the call is answered at said second 25 telephone, said selector switch including a control conductor, a line relay in said connector switch operated to one of its two positions in response to the seizure of said connector switch by said selector switch, a second relay operated to one of its two positions in response to the operation of said line relay to its said one position, means responsive to the operation of 30 said second relay to its said one position for conditioning said connector switch to complete said 35 connection, said second relay including contacts, closed when said second relay is operated to said one position, for applying a predetermined potential to said control conductor thereby to hold said selector switch operated, a normally interrupted path for applying said predetermined potential to said control conductor independently of said contacts, an alarm device, means operable during the establishing of said connection and maintained operated so long as said 40 talking loop is not interrupted at said second telephone for causing the operation of said alarm device and for partially completing said path, and means operative only when said call is answered for completing said path.

15. In a telephone system, a connector switch including a directing wiper, means for driving said wiper and bank contacts with which said wiper is adapted to engage, a line including a control conductor terminating at one of said bank contacts, a telephone on said line, a plurality of selector switches individually adapted to be operated to seize said connector switch, means comprising one of said selector switches for causing said first-named means to drive said wiper into 55 engagement with said one of said contacts, a relay operated to one of its two positions in response to the engagement of said wiper and said one of said contacts, means including said telephone for maintaining said relay in said one position, an alarm device operative in response to the operation of said one relay to said one position, and means for preventing said one of said selector switches from being released so long as said relay is in said one of said positions.

16. In a telephone system, a connector switch including a directing wiper, means for driving said wiper and bank contacts with which said wiper is adapted to engage, a line including a control conductor terminating at one of said bank 75

contacts, a telephone on said line, a plurality of selector switches individually adapted to be operated to seize said connector switch, means comprising one of said selector switches for causing 5 said first-named means to drive said directing wiper into engagement with said one of said contacts, a relay operated to one of its two positions in response to the engagement of said wiper and said one of said contacts, means including said 10 telephone for maintaining said relay in said one position, an alarm device operative in response to the operation of said one relay to said one position, and means comprising a portion of the control relays included in said connector switch 15 and normally operable in establishing said connection, for preventing said one of said selector switches from being released so long as said relay is in said one of said positions.

17. In a telephone system, a group of connector switches, each of said switches including a directing wiper, driving means for actuating the wiper and bank contacts with which the wiper is adapted to engage, a line including a control conductor terminating at one and the corresponding contact 25 of each of said switches, a telephone on said line, a plurality of selector switches individually adapted to be operated to seize any one of said connector switches, means comprising one of said selector switches for causing the driving means of 30 a seized connector switch to drive its associated directing wiper into engagement with the contact at which said control conductor terminates, a relay operated to one of its two positions in response to such engagement, means including said telephone for maintaining said relay operated, an alarm device operative in response to the operation of said one relay to said one position, and means for preventing said one of said selector switches from being released so long as said relay 35 is in said one of said positions.

18. In a telephone system, a group of connector switches, each of said switches including a directing wiper, driving means for actuating the wiper and bank contacts with which the wiper is adapted to engage, a line including a control conductor terminating at one and the corresponding contact 45 of each of said switches, a telephone on said line, a plurality of selector switches individually adapted to be operated to seize any one of said connector switches, means comprising one of said selector switches for causing the driving means of a seized connector switch to drive its associated directing wiper into engagement with the contact at which said control conductor terminates, a 50 relay operated to one of its two positions in response to such engagement, means including said telephone for maintaining said relay operated, an alarm device operative in response to the operation of said one relay to said one position, and means comprising a portion of the control relays included in the seized connector switch and normally operable in establishing said connection, for preventing said one of said selector switches from being released so long as said relay is in said one 55 of said positions.

19. In a telephone system, a first telephone, a second telephone, means for establishing a connection between said telephones on a call from said first telephone to said second telephone, said 60 connection comprising a talking loop adapted to be completed when the call is answered at said second telephone, said means normally being released when said talking loop is interrupted at said first telephone, an alarm device, means automatically operable to cause the operation of said alarm 65

device and to prevent the release of said first-named means, whereby calls to said second telephone may be traced by an operator, and means automatically operable to prevent the operation of said last-named means from affecting the release of said first-named means when said second telephone is busy at the time said call is initiated. 5

20. In a telephone system, a first telephone, a second telephone, means for establishing a connection between said telephones on a call from 10 said first to said second telephone, said connection comprising a talking loop adapted to be completed when said call is answered at said second telephone, said means normally being released when the talking loop is interrupted at said first 15 telephone, an alarm device, means automatically operable during the establishing of the connection and maintained operated so long as said talking loop is not interrupted at said second telephone for causing the operation of said alarm 20 device and for preventing the release of said first-named means, whereby calls to said second telephone may be traced by an operator, and means automatically operable to prevent the operation of said last-named means from affecting the release 25 of said first-named means when said second telephone is busy at the time said call is initiated.

21. In a telephone system, a first telephone, a second telephone, means for establishing a connection between said telephones on a call from 30 said first telephone to said second telephone, said connection comprising a talking loop adapted to be completed when the call is answered at said second telephone, said means normally being released when said talking loop is 35 interrupted at said first telephone, an alarm device, means responsive to the completion of said connection for causing the operation of said alarm device, and means responsive to the completion of said talking loop for preventing the 40 release of said first-named means by an operation performed at said first telephone, whereby calls to said second telephone may be traced by an attendant, said last-named means being inoperative in the event said second telephone is 45 busy at the time said call is initiated.

22. In a telephone system, a first telephone, a second telephone, means for establishing a connection between said telephones on a call from said first telephone to said second telephone, said connection comprising a talking loop adapted to be completed when said call is answered at said second telephone, said means normally being released when the talking loop is interrupted at said first telephone, an alarm device, 50 means responsive to the completion of said connection for causing the operation of said alarm device, and means responsive to the completion of said talking loop and effective so long as said talking loop is not interrupted at said second 55 telephone for preventing the release of said first-named means, whereby calls to said second telephone may be traced by an attendant, said last-named means being inoperative in the event said second telephone is busy at the time said call 60 is initiated.

23. In a telephone system, a first telephone, a second telephone, means for establishing a connection between said telephones on a call from said first telephone to said second telephone, 70 said connection comprising a talking loop adapted to be completed when said call is answered at said second telephone, said means normally being released when said talking connection is interrupted at said first telephone, an alarm de- 75

vice, means responsive to the completion of said connection for causing the operation of said alarm device, means responsive to the completion of said talking loop and effective so long as said talking loop is not interrupted at said second telephone for preventing the release of said first-named means, whereby calls to said second telephone may be traced by an attendant, and means for rendering said last-named means inoperative in the event said second telephone is busy at the time said call is initiated.

24. In a telephone system, a first telephone, a second telephone, means including a switch train for establishing a connection between said telephones on a call from said first to said second telephone, said connection comprising a talking loop adapted to be completed when said call is answered at said second telephone, said switch train including means for initiating the release of said connection when said talking loop is interrupted at said first telephone, an alarm device, means responsive to the completion of said connection for causing the operation of said alarm device, means operable when said talking loop is completed and maintained operated so long as said talking loop is not interrupted at said second telephone for preventing the operation of said second-named means from releasing said connection, whereby calls to said second telephone may be traced by an attendant, and means for rendering said last-named means inoperative in the event said second telephone is busy at the time said call is initiated.

25. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including means for completing the connection to the line associated with said second telephone and means normally operable to initiate the release of the connection in response to the interruption of said talking loop at said first telephone, an alarm device, means responsive to the operation of said second-named means for causing the operation of said alarm device and for preventing said third-named means from initiating the release of said connection, whereby calls to said second telephone may be traced by an attendant, and means for rendering said last-named means inoperative to affect the release of said first named means in the event said second telephone is busy at the time said call is initiated.

26. In a telephone system, a first telephone, a second telephone, means including a switch train and lines individually associated with said telephones for establishing a connection between said telephones on a call from said first telephone to said second telephone, said connection comprising a talking loop adapted to be completed when said call is answered at said second telephone, said switch train including a selector switch and a connector switch for completing the connection to the line associated with said second telephone, an alarm device, means responsive to the completion of said connection for causing the operation of said alarm device, means included in said connector switch and normally responsive to the interruption of said talking loop at said first telephone for releasing said connection, means operable when said talking

loop is completed for preventing said last-named means from releasing said selector switch, whereby calls to said second telephone may be traced by an attendant, and means including in said connector switch for rendering said last-named means inoperative in the event said second telephone is busy at the time said call is initiated.

27. In a telephone system, a first telephone, a second telephone, lines individually associated with said telephones, means including a selector switch and a connector switch, operable in the order named, for establishing a connection between said lines on a call from said first telephone to said second telephone, an alarm device, means responsive to the completion of said connection for causing the operation of said alarm device, said connection comprising a talking loop adapted to be completed when the call is answered at said second telephone, said selector switch including a control conductor, means comprising a relay in said connector switch for applying a predetermined potential to said control conductor to hold said selector switch operated, said relay being operable from one of its two positions to the other to remove said potential from said control conductor and thereby release said selector switch when said talking loop is interrupted at said first telephone, a battery reversing relay in said connector switch, and means including said battery reversing relay for maintaining said predetermined potential on said control conductor independently of said first-named relay.

28. In an automatic telephone system, a first telephone, a second telephone, lines individually associated with said telephones, means including a selector switch and a connector switch, operable in the order named, for establishing a connection between said lines on a call from said first telephone to said second telephone, said connection comprising a talking loop adapted to be completed when the call is answered at said second telephone, said connector switch being operative to select the line associated with said second telephone, said selector switch including a control conductor, means comprising a relay in said connector switch for applying a predetermined potential to said control conductor to hold said selector switch operated, said relay being operable from one of its two positions to the other to remove said potential from said control conductor and thereby release said selector switch when said talking loop is interrupted at said first telephone, an alarm device, a normally incomplete path for applying said potential to said control conductor to hold said selector switch operated independently of said relay, means responsive to the operation of said connector switch to select the line associated with said second telephone for causing the operation of said alarm device and for partially completing said path, and means responsive to the completion of said talking loop for completing said path and for holding said path completed so long as said loop is not interrupted at said second telephone.

29. In an automatic telephone system, a first telephone, a second telephone, lines individually associated with said telephones, means including a selector switch and a connector switch, operable in the order named, for establishing a connection between said lines on a call from said first telephone to said second telephone, said connection comprising a talking loop adapted to be completed when the call is answered at said

second telephone, said connector switch being operative to select the line associated with said second telephone, said selector switch including a control conductor, means comprising a relay in said connector switch for applying a predetermined potential to said control conductor to hold said selector switch operated, said relay being operable from one of its two positions to the other to remove said potential from said control conductor and thereby release said selector switch when said talking loop is interrupted at said first telephone, an alarm device, a normally incomplete path for applying said potential to said control conductor to hold said selector

switch operated independently of said relay, means responsive to the operation of said connector switch to select the line associated with said second telephone for causing the operation of said alarm device and for partially completing said path, means responsive to the completion of said talking loop for completing said path and for holding said path completed so long as said loop is not interrupted at said second telephone, and means for preventing said two last-named means from completing said path in the event the line associated with said second telephone is busy at the time it is selected. 5 10
